UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

DESIGN FOR A CUTLERY-HANDLE.

SPECIFICATION forming part of Design No. 22,483, dated May 30, 1893.

Application filed April 26, 1893. Serial No. 471,980. Term of patent 7 years.

To all whom it may concern:

Be it known that I, CHARLES F. SMITH, a citizen of the United States, residing at New Britain, in the county of Hartford and State of Connecticut, have invented and produced a new and original Design for Cutlery-Handles, of which the following is a specification, reference being had to the accompanying drawings, forming part thereof, in which—

Figure 1 is a side elevation of a knife or fork handle showing my design, and Fig. 2 is a plan view of the same.

A designates the body of the handle of the general contour in side view as shown in Fig. 1. At the ferrule end there are several plain

bands or beads and one larger band *b* of the contour shown. This larger band is ornamented by scroll and leaf ornaments. On the body of the handle adjacent to the ferrule end I arrange a series of ornaments *c* composed ²⁰ of lines extending in the general direction of the length of the handle with slight curves toward their ends.

What I claim is—

The design for cutlery handles, substantially as herein shown and described.

CHARLES F. SMITH.
